UNITED STATES PATENT OFFICE.

ALFRED TROSCH, OF ROCHESTER, NEW YORK, ASSIGNOR TO ARTHUR H. INGLE, OF ROCHESTER, NEW YORK.

POWER RAPID-TRAVERSE AND FEED MOTION FOR PLANERS.

1,369,501.

Specification of Letters Patent. Patented Feb. 22, 1921.

Application filed May 18, 1920. Serial No. 382,438.

To all whom it may concern:

Be it known that I, ALFRED TROSCH, a citizen of the United States, and resident of Rochester, county of Monroe, State of New York, have invented an Improvement in Power Rapid-Traverse and Feed Motions for Planers, of which the following description, in connection with the accompanying drawings, is a specification, like characters on the drawings representing like parts in each of the several views.

This invention relates to metal planers, and particularly to those of larger sizes adapted for use on relatively heavy and massive work. A principal object of the invention is to provide connections whereby the tool saddles and tool holders may be operated with a rapid traverse movement to bring them to operative position, and controlled by a relatively slower and separately actuated feed movement in the operation of the planer, and such connections equipped with controlling devices located at the saddle whereby the traverse and feed movements of the tools may be controlled by an operator from the locality of the saddle, and there being preferably provision whereby such control may also be effected from the side of the machine if desired. The foregoing and other objects and advantages of the invention will more fully appear from the following detailed description, and the distinctive features of novelty will be thereafter pointed out in the appended claims.

Referring to the drawings:

Figure 1 is a perspective view of a planer embodying the invention;

Fig. 2 is an enlarged partial front view showing an end of the cross rail with portions broken away;

Fig. 3 is an enlarged view showing the end of the cross rail looking from the right of Fig. 2;

Fig. 4 is an irregular section on the broken line 4—4 of Fig. 3; and

Fig. 5 is an enlarged partial front view showing a part of the saddle with the controlling handles.

The planer bed 1 has slidably fitted thereon a usual table 2 and is equipped with usual spaced apart uprights 3, 4 joined at their tops by a horizontal rail 5. The uprights 3, 4 have fitted thereon for vertical adjustment and movement a cross rail 6 bearing for adjustment, and operative movement, tool sad-

dles 7, 8, and as shown these uprights are also equipped with side tool heads 9. It is desirable and important that provision be made whereby the operator may control the rapid traversing and also the operative movements of the tools from a point adjacent thereto so that he may have the work under close observation in the manipulation of the tools and the present invention provides means whereby this control may be effected in a convenient manner from either saddle. Power for the rapid traverse movements of the saddles and tool holders is derived from a motor 10 mounted on the top rail 5 which through reducing gearing 11 drives constantly a short shaft 12 journaled on the top rail intermediate its length. The shaft 12 has loosely fitted thereon spaced apart pinions 13, 14 which are selectively engageable with said shaft by a double ended friction clutch slidably fitted on the shaft. The gear 13 engages and drives a gear 16 fixed on a shaft 17 horizontally journaled on the top rail and extending the entire distance between the uprights. The shaft 17 also has a gear 18 fixed thereon which may be driven from the gear 14 in a reverse direction relative to the drive of the gear 16 by means of an intermediate gear 19. The shaft 17 through bevel gears 20 drives a shaft 21 vertically journaled at the end of the upright 4 and extending downward to the base thereof. The shaft 21 has slidably keyed thereon a bevel pinion 22 which operatively engages a bevel gear 23 fixed at the inner end of a short shaft 24 journaled in a bracket 25 of the cross rail, the pinion 22 being also held to travel with the cross rail and to remain in mesh with the gear 23. The shaft 24 has fixed at its outer end a pinion 26 which engages a relatively large gear 27 loosely journaled on a short shaft 28 fixed in the end of the cross rail. The gear 27 engages a series of pinions 29, 30, 31 loosely mounted on end portions of the feed screws 32, 33 and the feed shaft 34 respectively, the feed screws being adapted for operating the respective saddles along the cross rail and the feed shaft 34 for imparting vertical movement to the tool holders on the saddles in accordance with the usual practice. The pinions 29, 30, 31 are equipped at their outer sides with clutch faces 35 which are engageable by co-operative faces 36 at one end of clutch hubs 37 slidably keyed on the respec-

tive shafts 32, 33, 34. These clutch hubs are operated by shifters 38 borne by shafts 39 extending to the outside of the housing and equipped with handles 40. For controlling 5 this rapid traverse movement so as to engage it in either direction or to disengage it, the double friction clutch hub 15 is equipped with an arm 41 having connected thereto a rod 42 which extends to the side of the machine where it is engaged with a crank 43 fixed at the upper end of a rock shaft 44 vertically journaled to bracket bearings of the upright. This rock shaft 44 has fixed 10 to a lower end portion thereof a handle 45 whereby it may be actuated from a position adjacent the upright. For operating this rock shaft and thus controlling the rapid traverse from either of the saddles, this shaft 44 has slidably keyed thereto a bevel pinion 20 46 which is journaled in, and held from endwise movement by a sleeve 47 in the end of the cross rail. This pinion engages a bevel pinion 48 fixed on a short shaft 49 horizontally journaled at the end of the cross rail. 25 The shaft 49 has fixed to its other end an arm 50 the outer end of which engages with a link 51. The other end of the link 51 is pivoted to the outer end of an arm 52 fixed to a rock shaft 53 which is horizontally journaled in the cross rail and extends the length 30 thereof. The shaft 53 has slidably keyed thereon bevel pinions 54, there being one thereof journaled at a side of each saddle and held to travel therewith. Each of these 35 pinions 54 is engaged by a bevel pinion 55 journaled in the saddle and having rigid therewith a handle 56 extending at the front of one side of the saddle. Thus by operating either of these handles 56 at either of the 40 saddles on the cross rail, the rapid traverse for either direction of movement may be thrown into engagement or disconnected at will. For imparting feed movement to the feed screws and shafts 32, 33, 34, power is 45 taken from a shaft 57 vertically journaled alongside the upright 4 and oscillated from a feed box (not shown) at the base of the machine in usual manner on each stroke of the table. The shaft 57 has slidably keyed 50 thereon and carried by the cross rail a bevel pinion 58 which meshes with a pinion 59 fixed at the inner end of a short shaft 60 journaled in bearings at the outer end of the cross rail. The shaft 60 has fixed at 55 its outer extremity a feed block 61 having a link connection 62 to a crank pin 63 borne by a driving bar member 64 of a clutch device adapted to engage a relatively large gear 65 loosely journaled on the shaft 28. 60 To effect this clutch connection the clutch bar member 64 is loosely journaled on a hub 65^a of the gear 65 and it has pivoted at an end thereof a short rock shaft 66 bearing at its outer end an expander block 67 which 65 engages the flanged ends of a clutch ring 68

coöperative to frictionally engage an internal clutch surface 65^b of the gear 65. The rock shaft 66 has fixed at its inner end an arm 69 constituting a clutch finger and having at its inner end a pin 69^a engaged by a cone 70 slidable on a reduced extension of the gear hub 65^a. The cone 70 is engaged by a shipper yoke 71 pivoted at 72 to a bracket 73 borne by the cross rail. This shipper yoke has a downward extension past 75 its pivot which bears a pin 74 engaging in a cam slot 75 formed in a cam head 76 which is fixed to a short rock shaft 77 horizontally journaled at the end portion of the cross rail. The shaft 77 has fixed thereto an arm 78, 80 the outer end of which is engaged with a link bar 79, the other end of which engages an arm 80 fixed to a shaft 81 horizontally journaled in the cross rail and extending the length thereof. The shaft 81 has slidably 85 keyed thereon bevel pinions 82, there being one fitted at the side of each saddle and held for movement therewith. Each pinion 82 meshes with a coöperative pinion 83 journaled in a bracket of the saddle and having a handle 84 rigid therewith, these handles 84 preferably and as shown, being located on the same side of the saddle as the handles 56 and in the present embodiment being directly thereover. Thus by manipulating a handle 84 at either saddle the gear 65 may be thrown into engagement with the oscillating feed movement for transmitting the same to the feed screws and shafts. This transmission from the gear 65 to the feed 90 screws and shaft when the feed is to be employed, is effected through pinions 85 loosely mounted on the ends of the respective shafts 32, 33, 34. These pinions may be formed interiorly as click boxes (not shown) in accordance with the usual practice so as to transmit only a one way movement in either direction at will to the feed shafts, this one way movement in the present case being transmitted to a clutch hub 86 loose on the 95 shaft and having a clutch face with which a clutch face 36^a on the end of the clutch hub 37 coöperates when said clutch hub is thrown to the right as seen in Fig. 4. Thus by adjusting the clutch hub 37 on either of the feed shafts 32, 33, 34 to the right (Fig. 4), a step-by-step feed movement at a relatively slow rate may be transmitted, to actuate either of the cross rail saddles or tool holders when the upper handle 84 of such saddle is moved to engage the feed. Likewise with a clutch hub 37 adjusted to the left (Fig. 4) the power rapid traverse may be engaged for either saddle upon actuation of the lower handle 46 on such saddle, it being noted that there is thus no possibility of the feed and rapid traverse to any feed shaft being engaged at the same time, and when the clutch hub 37 is in intermediate 100 position both the feed and rapid traverse are 105 110 115 120 125 130

disengaged. Thus the feed and rapid traverse movements of each saddle and the tool holder thereon are under complete and instant control of the operator from a position 5 adjacent the saddle and where he can keep the work under close observation. I am aware that the invention may be embodied in other specific forms without departing from the spirit or essential attributes thereof, 10 and I therefore desire the present embodiment to be considered in all respects as illustrative and not restrictive, reference being had to the appended claims rather than to the foregoing description to indicate the 15 scope of the invention.

Having described my invention, what I claim as new and desire to secure by Letters Patent is:

1. The combination with a planer table 20 and cross rail, of a saddle bearing a tool holder mounted on said cross rail, feed connections and rapid traverse connections to the saddle, and means borne by the saddle for controlling said connections.

2. The combination with a planer table 25 and cross rail, of a saddle bearing a tool holder mounted for operative movement on the cross rail, rapid traverse connections to said saddle including reversing means, and means for controlling said rapid traverse 30 connections to move the saddle in either direction having an operating element borne by the saddle and adapted for manual actuation.

3. The combination with a planer table 35 and cross rail, of a saddle bearing a tool holder mounted for operative movement on the cross rail, rapid traverse connections to said saddle including a direction reversing device, and controlling connections from said reversing device to the saddle and having an operating lever borne by the saddle.

4. The combination with a planer table, of a saddle mounted for operative movement 45 with respect thereto, rapid traverse connections to the saddle including a disconnecting and direction reversing clutch, and a manual operating device borne by the saddle for controlling said clutch.

5. The combination with a planer table 50 and a saddle bearing a tool holder mounted for operative movement with respect thereto, of rapid traverse connections to the saddle including a reversing device, separate feed connections to the saddle, and means 55 borne by the saddle for manually controlling said rapid traverse connections and said feed connections selectively.

6. The combination with a planer table 60 and a saddle bearing a tool holder operatively mounted with respect thereto, of rapid traverse connections to the saddle including a direction reversing and disconnecting clutch, separate connections for imparting step-by-step feed movement to the saddle, 65 and means borne by the saddle for controlling said clutch of the rapid traverse connections and also for controlling said feed connections to engage the same selectively.

7. The combination with a planer table 70 and cross rail, of a plurality of saddles bearing tool holders mounted for operative movement thereon, rapid traverse connections to said saddles including direction reversing means, separate feed connections to 75 the saddles, and controlling connections from said clutch of the rapid traverse and also from said feed connections terminating in levers borne by the saddles for operatively engaging the rapid traverse in either 80 direction or the feed connection to the saddles selectively.

8. A planer, comprising a table cross rail and upright structure on which the cross rail is mounted, a plurality of saddles bearing tool holders mounted on the cross rail, rapid traverse connections to the saddles including direction reversing means mounted at the top of the housing, separate feed connections to the saddles, and manual operating members borne by the respective saddles and having connections for operatively engaging the rapid traverse in either direction or the feed connections to the saddles selectively. 95

In testimony whereof, I have signed my name to this specification.

ALFRED TROSCH.
